UNITED STATES PATENT OFFICE.

SAMUEL S. GAY, OF SEDRO WOOLLEY, WASHINGTON.

RAIL-JOINT.

1,177,242.

Specification of Letters Patent. Patented Mar. 28, 1916.

Application filed November 24, 1915. Serial No. 63,244.

To all whom it may concern:

Be it known that I, SAMUEL S. GAY, a citizen of the United States, residing at Sedro Woolley, in the county of Skagit, State of Washington, have invented a new and useful Rail-Joint; and I do hereby declare the following to be a full, clear, and exact description of the invention, such as will enable others skilled in the art to which it appertains to make and use the same.

This invention relates to an improved rail joint, and an object of the invention is to provide a device of this nature consisting of a dove-tailed joint having means to prevent one or the other of the joined adjacent rails from moving downwardly in advance of the other, thereby avoiding a shearing action upon the key connecting means which join the adjacent rail sections.

Another object of the invention is the provision of a key elongated or elliptical in cross section, to prevent the key from gradually rotating, which, if capable of gradually rotating, would eventually permit the locking member of the key to fall out or dislodge from the key.

In practical fields the details of construction may necessitate alterations, falling within the scope of what is claimed.

The invention comprises further features and combination of parts, as hereinafter set forth, shown in the drawings and claimed.

In the drawings: Figure 1 is a plan view of a section of a pair of rails, showing the improved joint as applied to the adjacent ends of two sections of each rail. Fig. 2 is an enlarged detail perspective view illustrating the structure of the rail joint connecting the adjacent ends of two rail sections, showing the parts of the joint disassembled.

Referring more especially to the drawings, 1 and 2 designate the adjacent sections of each rail, and as shown in Fig. 2 the base of the rail section 2 is cut away as shown at 3. The tread and the web of the rail section 2 is provided with a vertical bifurcation 4 above and adjacent the cutaway portion 3. The upper adjacent faces 5 of the arms 6 are inclined or beveled downwardly toward each other, as shown, and these arms 6 below the tread are provided with adjacent registering openings 7, which are elliptical or elongated. In other words, the openings 7 are formed in the web of the

rail section 2, which web is considerably thickened, so that the bifurcation 4 may be formed vertically therein. The web of the rail section 1 is provided with a thickened portion 8^a. However, from a to b: the web 8^b is of the usual thickness. In other words, upon both sides of the web of the rail section 1, the thickened portion 8^a of the web terminates at a, thereby causing the formation of the shoulders 8^c, against which the end faces 8^a engage or abut, when the web from a to b of the rail section 1 enters the bifurcation 4. The tread 8 of the rail section 1 is cut away as shown at 9 upon both sides, and the opposite faces of the tread 70 where it is cut away are beveled or inclined downwardly and toward each other to a point indicated at 11, so that said opposite inclined faces 12 may engage the adjacent correspondingly inclined faces 5 of the upper adjacent portions of the arms 6, to assist in preventing the rail section 1 from moving downwardly, and the rail section 2 from moving upwardly. When the web portion beyond the thickened portion 8^a of 30 the rail section 1 is received in the bifurcation 4, the lower edges 12^a engage at 12^b upon the base of the rail section 1, which prevents downward movement of the rail section 2 and prevents upward movement of 75 the rail section 1. The engaging parts 12^a and 12^b and the engaging inclined faces 5 and 12 also prevent or avoid a shearing action on the key 13, which may be received in the openings 7. The web 8^b of the rail section 1 is provided with an opening 7^a, corresponding in shape to the openings 7, and designed to register with the openings 7 when the web 8^b is received in the bifurcation 4. The key 13 has a head 16 at one end 90 and a rectangular opening 17 extending transversely of the other end, which opening is designed to receive the wedge member 18. The key 13 is made elongated or elliptical in cross section to correspondingly fit the 100 openings 7 and 7^a and to prevent the key 13 from turning. The wedge member 18 is designed to be driven down into the opening 17, thereby drawing the arms 6 tight against the inclined faces 12 and against the web 8^b 105 of the rail section 1, to insure a tight joint. The wedge member 18 has an opening 20 in its lower end to receive the cotter pin 21, to prevent upward displacement of the wedge member. One side of the tread of the rail 110

section 2 is formed with a recess 22, to permit the wedge 18 to enter the rectangular opening 17 of said key.

The invention having been set forth, what is claimed as new and useful is:

1. In combination, a pair of adjoining rail sections, one of the rail sections having its base cut away so that the base of the other rail section may be received in the cut away portion, the rail section having the cut away portion having its web thickened and being provided with a vertical bifurcation which also extends upwardly through the tread, the upper portions of the adjacent faces of the bifurcation being inclined or beveled downwardly toward each other, the other rail section having a thickened web, which, toward the end of the rail section is cut away to leave the usual thickness of web to enter the bifurcation in the other rail section, the tread above said usual thickness of web being cut away, the opposite faces of which cut away portion being inclined downwardly to engage the inclined faces of said bifurcation, to assist in preventing movement of the rail sections relative to each other, the lower edges of the arms formed by said bifurcation engaging the base of the rail section with its tread cut away to assist in preventing movement of the rail sections vertically relative to each other, the webs of both rail sections having registering elongated shaped openings, and means engaging said openings to hold the sections connected.

2. In combination, a pair of adjoining rail sections, one of the rail sections having its base cut away so that the base of the other rail section may be received in the cut away portion, the rail section having the cut away

portion having its web thickened and being 40 provided with a vertical bifurcation which also extends upwardly through the tread, the upper portions of the adjacent faces of the bifurcation being inclined or beveled downwardly toward each other, the other 45 rail section having a thickened web, which, toward the end of the rail section is cut away to leave the usual thickness of web to enter the bifurcation in the other rail section, the tread above said usual thickness of 50 web being cut away, the opposite faces of which cut away portion being inclined downwardly to engage the inclined faces of said bifurcation, to assist in preventing movement of the rail sections relative to 55 each other, the lower edges of the arms formed by said bifurcations engaging the base of the rail section with its tread cut away to assist in preventing movement of the rail sections vertically relative to each 60 other, the webs of both rail sections having registering elongated shaped openings, and means engaging said openings to hold the sections connected, said means comprising a key, elongated in cross section to correspondingly fit said openings and having a head at 65 one end and a rectangular opening at the other end, a wedge to engage said opening to hold the key in place, and a cotter pin passing transversely of the lower end of the 70 wedge to hold the wedge in position.

In testimony whereof I have signed my name to this specification in the presence of two subscribing witnesses.

S. GAY.
